UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

YARN CLEANER FOR SPOOLERS.

Application filed August 8, 1927. Serial No. 211,363.

This invention relates to a yarn cleaner for spoolers, spinning or other similar machines, the general purpose of which is to remove slubs, beads or bunches of fibre 5 from the yarn before it is wound upon the yarn receiver.

The object of the invention is to provide a simple and efficient construction of such a device which may be readily adjusted 10 properly to position the comb teeth with respect to the guide rod and in which the comb may be readily swung out of position to permit the cleaning of the comb and then 15 swung back to position without disturbing the adjustment.

These and other objects and features of the invention will appear more fully from the accompanying description and drawings and will be particularly pointed out in the 20 claims.

Two forms of the device embodying the broad principles of the invention but differing in specific features are illustrated.

In the drawings:

25 Fig. 1 is a front elevation of one form of the device embodying the preferred form of the invention.

Fig. 2 is a rear elevation of the construction shown in Fig. 1.

30 Fig. 3 is a side elevation of the same construction looking toward the right of Fig. 1.

Fig. 4 is a front elevation of another form of construction.

Fig. 5 is a rear elevation of the construction shown in Fig. 4.

Fig. 6 is a side elevation of the same construction looking toward the left of Fig. 4.

The construction illustrated in Figs. 1 to 3, inclusive, includes a two-part bracket 40 supporting the various elements of the yarn cleaner and which is adapted to be clamped to the usual traverse rod 1 of a spooler or similar machine. The main part 2 of the bracket and the clamping part 3 are each provided with substantially semi-circular transverse recesses facing each other and adapted to embrace the traverse rod. Flange portions 4 and 5 depend from the bracket parts and are secured together by a clamping bolt 6 so that when the bracket is in place on the traverse rod, the bracket parts are rigidly secured together and rigidly secured to the traverse rod.

55 A toothed comb is employed for removing the slubs, etc., from the yarn and the

yarn in its passage through the comb is guided over a main guide rod 7 and an auxiliary guide rod 8, both of which are secured to and project laterally from the main bracket part 4, both herein shown as driven 60 into holes formed in the bracket.

In this type of device it is necessary that the line of comb teeth be accurately spaced from the main guide rod 7, that the line of the comb teeth be parallel to the main guide 65 rod, that suitable provision be made for varying as required the space between the line of comb teeth and the main guide rod, and that provision be made for swinging the comb member away from the guide rod 70 to permit the cleaning of the comb or the removal of the slubs, etc., therefrom and then for returning the comb member to operative position without disturbing any of the adjustments. 75

The comb member, in the form under consideration, is shown as comprising, first, a flat blade 9 extending generally parallel with the guide rod and having a rearwardly bent or formed ear 10 and, second, a comb proper shown as a flat plate 11 fitting against one face of the blade 9 and provided at its lower edge with a row of comb teeth 12. In the construction illustrated, the blade 9 normally stands substantially 80 vertical and consequently the lower edge of the plate 11 is bent forwardly and downwardly as shown at 13, so that the comb teeth may present the angle required to allow the slubs, etc., to slide up thereon during the passage of the yarn. The comb plate 11 is pivoted at one end on the bolt 14 to the plate 9 and means are provided at the other end for adjustably securing the comb to the blade. For this purpose 85 the comb plate is provided with an enlarged opening 15 fitting over a bolt 16 passing through the blade 9. 90

The bracket part 2 is provided at the rear with a vertically split extension 17 having 100 a vertical cylindrical bore and at the rear thereof a transverse clamping bolt 18. A comb member support is provided having a cylindrical shank 19 fitting this bore and a head 20 vertically slotted to receive the ear 10 of the blade 9. A pivot screw 21 passing through the head 20 and the blade 10 permits the comb member to swing into 105 and out of cooperation with the guide rod 7. The downward swinging movement of 110

the comb member is limited by a projection 22 on the blade 9 coming into contact with the bracket.

The comb member support is thus both vertically adjustable and rotarily adjustable on its vertical axis in the bracket to adjust the line of comb teeth with respect to the guide rod 7 both to provide the proper spacing and to secure horizontal parallelism, and when in adjusted position this support is rigidly locked by the clamping bolt 18. The vertical pivotal adjustment of the comb plate 11 on the blade 9 enables the line of comb teeth to be adjusted to vertical parallelism with the guide rod 7.

It will thus be seen that any required adjustment may be accurately and readily made and that the comb member may be swung upwardly on the pivot 21 to permit the cleaning of the comb and then return to operative position without disturbing the adjustment. Furthermore, if the comb teeth become broken or damaged, a new comb plate may readily be substituted.

In Figs. 4 to 6, inclusive, another form of device is illustrated embodying certain features of the invention. In this construction the bracket comprising the main part 23 and the clamping part 24 secured to the traverse rod 1 by the clamping bolt 25 is substantially the same as that already described. The comb support has a similar cylindrical shank 26 clamped by the bolt 27 in the split rearward extension of the bracket, but in this case the head 28 of the support is provided at the front with a rearward and upward inclined face 29 normally extending parallel to the guide rod 30. Upon this inclined face is pivoted the comb member, which in this case is a single blade 31 pivoted on the screw stud 32 extending into the head 29. This plate is provided at its lower edge with a row of comb teeth 33 and as the blade is inclined, the comb teeth are properly inclined with respect to the guide rod. The vertical adjustment and rotary adjustment of the comb support on its vertical axis in the bracket are secured in the same manner as already described.

The comb member in this case is swung upwardly on the pivot 32 to permit the cleaning of the comb and downwardly to bring it into operative position. Adjustable means are provided in this case for limiting the downward swinging movement of the comb and are herein shown as a set screw 34 threaded through a lug 35 in the bracket, abutting the edge of the blade 31 and locked in adjusted position by the lock nut 36. This adjustment not only limits the downward movement of the comb member, but also enables it accurately to be positioned in vertical parallelism with the guide rod 30. A pin 37 in the comb member 31 limits the upward swinging movement thereof.

The comb member is preferably held in its normal operative position against the set screw 34 by a spring. The operative means readily swing the comb member to cleaning position against the tension of this spring, but this spring insures automatic return of the comb member to operative position. A suitable helical spring for this purpose is shown at 38 seated in the head 29 surrounding the screw stud 32 and engaging at one end the head and at the other end the comb member.

In both forms it will be seen that a relative vertical adjustment is provided between the comb member and the guide rod to secure the proper spacing, a rotary adjustment on a vertical axis of the comb member is provided to bring the comb into horizontal parallelism with the guide rod, and a further adjustment is provided to bring the comb member into vertical parallelism with the guide rod and in both the comb teeth extend at the proper angle with respect to the guide rod.

Having thus described the invention, what is claimed as new, and desired to be secured by Letters Patent, is:

1. A yarn cleaner for spoolers and similar machines comprising a bracket, a guide rod projecting laterally therefrom and over which the yarn passes, a support vertically adjustable and rotarily adjustable on its vertical axis in the bracket, a comb member pivoted on said support to swing into and out of cooperative relation with the guide rod, and means for limiting the downward swinging movement of the comb member.

2. A yarn cleaner for spoolers and similar machines comprising the construction defined in claim 1, in which the bracket is provided with a vertical, cylindrical bore and the support is provided with a cylindrical shank fitting said bore and in which means are provided for locking the shank of the support to the bracket in the required vertical and rotary adjustment.

3. A yarn cleaner for spoolers and similar machines comprising a bracket presenting a support, a guide rod projecting laterally from the bracket and over which the yarn passes, a comb member including a blade and a comb, the said comb pivoted at one end on the blade, means for adjustably securing the comb at the other end to the blade, and means for effecting a relative vertical adjustment of the comb member and guide rod.

4. A yarn cleaner for spoolers and similar machines comprising the construction defined in claim 1, in which the comb member comprises a blade and a comb with the blade pivoted on the support and with the comb pivoted at one end on the blade, together with means for adjustably securing the comb at the other end to the blade.

5. A yarn cleaner for spoolers and similar machines comprising a bracket, a guide rod projecting laterally therefrom and over which the yarn passes, a support on the bracket, a blade pivoted on said support to swing toward and away from the guide rod, a comb pivoted at one end on the blade, and means for adjustably securing the comb at the other end to the blade.
- 10 6. A yarn cleaner for spoolers and similar machines comprising a bracket having a split, vertical bore therein, a support having a cylindrical shank fitting said bore and permitting the support to be adjusted vertically and rotarily on its vertical axis in the bracket, means for clamping the bracket and support in adjusted position, a comb member mounted upon said support and a guide rod projecting laterally from the bracket and cooperating with the comb member to effect the cleaning of the yarn.
- 15 7. A yarn cleaner for spoolers and similar machines comprising a bracket, a guide rod projecting laterally therefrom and over which the yarn passes, a support carried by the bracket and both vertically adjustable with respect thereto and rotarily adjustable on its vertical axis, and a comb carried by the support and adjustable with respect thereto to bring its teeth into vertical parallelism with the guide rod.

In testimony whereof, I have signed my name to this specification.

HARRY A. DAVIS.
